UNITED STATES PATENT OFFICE.

WILHELM HUBRICH, OF BERLIN, GERMANY.

MANUFACTURE OF TURNED SHOES.

SPECIFICATION forming part of Letters Patent No. 769,163, dated September 6, 1904.

Application filed May 25, 1903. Serial No. 158,731. (No model.)

To all whom it may concern:

Be it known that I, WILHELM HUBRICH, shoe manufacturer, a citizen of the German Empire, and a resident of No. 26 Kaiser Wilhelmstrasse, in the city of Berlin, Kingdom of Prussia, and Empire of Germany, have invented certain new and useful Improvements in the Manufacture of Turned Shoes, of which the following is a specification.

In the manufacture of light shoes, especially house-shoes or house-slippers, many drawbacks still show themselves. On the one side the manufacture of the same is too expensive; on the other, the manufacture by the working hands engaged in the same at present is beset with difficulties. To remove these drawbacks, the object of this invention is to provide shoes of the kind which in addition to their lightness are cheap and quite as durable as any of those put on the market hitherto. This is attained by providing a sole of pasteboard, linoleum, leather, &c., on the outside with a covering of canvas, leather, &c., which latter is stitched to the upper leather and any lining of the same in such a way that this seam is removed from the edge of the sole a distance equal to the thickness of the sole.

The invention is illustrated in the accompanying drawings, in which—

Figure 1 shows the shoe with upper leather cut off on the line C D of Fig. 2, while Fig. 2 is a sectional view on the line A. B of Fig. 1. Fig. 3 shows the mode of stitching together the upper leather and covering of the sole; and Fig. 4 shows in a sectional view, on an enlarged scale, a piece of sole with the covering pasted on and upper leather stitched on.

For manufacturing this shoe the upper *c*, with the lining *d*, is placed under the sole *a*, the covering *b* is glued to the same, Fig. 3, and now upper leather, the lining, and the covering of the sole are stitched together at a distance from the edge of the sole equal to

the thickness of the same. A backstitch varying in width according to the thickness of the sole is best suited for this. Now the upper stuff is turned—that is to say, the upper leather *c*, together with the covering *b*, projecting over the edge of the sole, is bent around the sole. The seam *f*, over the sole, will thus be close to the edge, Figs. 2 and 4, so that the foot will not step on the seam. As can be seen, especially from Figs. 2 and 4, the real sole *a*, of pasteboard or other material, is provided on the outside with a covering *b*, of canvas, leather, or other material, which is stitched together with the upper leather *c* and any lining of the same at *f* in the above-described manner, Fig. 3. After the shoe has been turned, Fig. 4, the edges *c'* of the upper leather, lining, and covering can be united by basting or tacking threads on the inside of the sole, Fig. 1; but this is not absolutely necessary, as the whole is already tightly stretched around the sole *a* without this. After putting in a filling *e* there is laid over the whole inner breadth of the shoe an insole of any material.

What I claim as my invention, and desire to secure by Letters Patent of the United States, is—

The process of making turned shoes consisting in pasting a covering *b* of canvas, leather or the like to the outside of the sole, stitching the upper *c* together with the said covering at a distance from the edge of the sole equal to the thickness of the sole and turning the shoe, substantially as set forth.

In witness whereof I have hereunto signed my name, this 30th day of April, 1903, in the presence of two subscribing witnesses.

WILHELM HUBRICH.
